UNITED STATES PATENT OFFICE.

EDWIN D. TUCKER, OF NEW YORK, N. Y., ASSIGNOR, BY DIRECT AND MESNE ASSIGNMENTS, TO ROBERT HOE AND CHARLES W. CARPENTER, UNDER THE FIRM-NAME OF R. HOE & COMPANY, OF NEW YORK, N. Y.

CASTING-BOX.

SPECIFICATION forming part of Letters Patent No. 709,942, dated September 30, 1902.

Application filed October 7, 1899. Serial No. 732,846. (No model.)

To all whom it may concern:

Be it known that I, EDWIN D. TUCKER, a citizen of the United States, residing at New York city, county of New York, and State of New York, have invented certain new and useful Improvements in Casting-Boxes, fully described and represented in the following specification and the accompanying drawings, forming a part of the same.

10 This invention relates to certain improvements in casting-boxes, and more particularly to the type of boxes which are used in printing-offices for casting stereotype-plates.

In stereotyping casting-boxes as now ordinarily constructed the position of the matrix and the length of the casting are determined by what is ordinarily known as a "head-gage," this gage being a strip or bar which is located at the inner end of the box and usually pivoted thereto. In an ordinary curved casting-box the head-gage is provided with handles which are seized by the operators when the box is opened, the head-gage being thus turned on its pivot to throw the cast plate forward, so that it can be readily grasped and removed from the box. The boxes ordinarily used are arranged to stand in vertical position when the molten metal is poured. After the pouring has taken place the box is swung into a horizontal position, and the cope or cover is then opened. The operators (for there are usually two) then reach down and rock the head-gage to displace the cast plate. This requires a separate movement on the part of the operators, and, furthermore, since the handles of the head-gage are necessarily short considerable force is required in order to throw the cast plate forward, so that its outer end can be readily grasped. After this has been done the operators seize the outer end of the plate and remove it from the box. These operations require some little time, and, as is well understood, time is of essential importance in the stereotyping operation. In newspaper-offices every effort is made to shorten the time between the closing of the forms and the appearance of the completed paper on the street, the object being to delay the closing of the forms 50 as long as possible, so as to get in the late

news. In large offices, therefore, where a considerable number of plates have to be cast, strenuous effort is made to save time between the closing of the forms and the starting of the presses, and particularly in the stereotyping operation.

The object of this invention is to produce a casting-box in which the operation of displacing the cast plate in the casting-box may be more quickly and easily performed, thereby saving time in the operation of casting.

A further object of the invention is to produce a casting-box in which the cast plate shall be automatically displaced or thrown forward by the movement of the cope or cover 60 in opening the box.

With these and other objects in view the invention consists in certain constructions and in certain parts, improvements, and combinations, as will be hereinafter described and 70 then pointed out in the claims hereunto appended.

In the accompanying drawings, which form a part of this specification and in which like characters of reference indicate the same 75 parts, Figure 1 is a side view of so much of a casting-box as is necessary to illustrate one form of the invention. Fig. 2 is a plan view of the construction shown in Fig. 1. Fig. 3 is a vertical sectional view of the construction shown in Fig. 1, the box being shown as partly open and the gage thrown forward to displace the plate. Fig. 4 is a view similar to Fig. 3, but illustrating the operation of the parts as the cope or cover of the box is being 80 closed. Fig. 5 is a detail sectional view illustrating a modification of the invention. Fig. 6 is a detail sectional view of the construction shown in Fig. 5, the parts being shown in the position they occupy as the box is being 85 opened and the gage is being moved to displace the plate. Fig. 7 is a detail sectional view illustrating the modification shown in Fig. 5 and showing the parts in the position they occupy as the cope or cover is being 90 closed. Fig. 8 is an elevation, partly in section, of a somewhat different form of box and illustrating another form of the displacing devices. Fig. 9 is a detail sectional view.

In the accompanying drawings, 1 indicates 100

the body or mold proper, which in the form of the invention shown is of the ordinary curved or semicircular form and intended for casting curved plates, such as are now universally used on fast rotary presses.

2 indicates the cope or cover of the box, which is preferably pivoted to the body. The construction by which the cover is pivoted to the body may be of any ordinary or desired form. In the construction shown the body is provided with ears 3 and the cover with ears 4. Through these ears runs an ordinary pivot-rod 5, which is secured in position by means of nuts 6.

15 The body of the box is provided with the usual side gages, which are omitted from the illustration for the sake of clearness, and with a head-gage 7, the purpose of which is to close the inner end of the box and to determine the 20 position of the matrix and the length of the cast plate. The head-gage may be secured to the box in any suitable or desired manner, but is preferably pivoted thereto, as shown, the gage being provided with pins, which are 25 let into short slots 8, located in the body of the box. In the form of the invention shown in Figs. 1 to 4 the upper ends 9 of the head-gage 7 extend considerably above the body of the box, for a purpose to be hereinafter described. In the ordinary form of box, as has 30 been indicated, the head-gage is moved, after the cast is made and the box is opened, by handles in order to displace the cast plate and throw it forward, so that it may be seized 35 by the operators. These handles must necessarily be short in order not to interfere with the working of the box, and considerable power is required to move the gage and displace the casting, because the short handles afford very little leverage. Furthermore, since the handles are at the bottom of the box the operators have to bend down to 40 reach them. As the bottom of the box when the box is swung into a vertical position is 45 near the floor, the handles are not easily reached by the operators, nor are the operators when they have reached the handles in an advantageous position for exercising the necessary power required to start the cast plate. In the present invention means are 50 provided by which the head-gage is operated independently of its handles, which may or may not be omitted. The operating means for the head-gage may be varied very considerably. In the form of the machine shown 55 in Figs. 1 to 4 the extensions 9, before referred to, lie in the path of projections 10, carried by the cover. These projections are preferably pivoted between ears 11, carried 60 by a bracket 12, bolted to the cover. There is also preferably provided a spring 13, which is secured to one of the ears 11 and bears upon the projections 10, for a purpose to be hereinafter described. In the construction shown 65 in Figs. 1 to 4 as the cover of the box is raised after the pouring of the metal has taken place and the box has been returned to a horizon-

tal position the projections 10 will strike the ends 9 of the head-gage and turn the same on its pivot. The movement of the head-gage 70 causes the cast plate P to be thrown forward, the position of the parts at the time the head-gage is at the end of its forward movement being shown in Fig. 3. As the cover of the box is turned still farther on its pivot in order 75 to fully open the box the projections 10 slip over the ends 9 of the head-gage 7. The end of the plate now projects considerably from the forward end of the box, and the plate can be readily seized and removed by the operators. After the plate is removed the head-gage is thrown back into position and the cover of the box closed. As the cover is swinging down into its closed position the 80 projections 10 are allowed by the springs 13 85 to swing on their pivots sufficiently to pass the projecting ends 9 of the head-gage, and after they have passed these ends the springs 13 cause the projections to snap back into their normal position. 90

In the construction shown in Figs. 5, 6, and 7 the operating means for the head-gage are differently arranged. In this form of the construction the cover 2 of the box is provided at its rear end with an angular arm 14. This 95 arm is preferably perforated, so that the pivot-rod 5 passes through it. This angular arm has a socket 15 formed in its ends, in which socket is located a projection 16, this projection being in the form of a spring-seated pin, 100 the spring which controls its movement being marked 17. The projection is limited in its movement by means of a pin 19, which works in a slot 20 in the angular arm. In this form of the invention the body of the 105 box has fixed thereto a slotted plate 21, the said plate being arranged just back of the head-gage, as is clearly shown in Figs. 5, 6, and 7. The slotted plate is held in position and the extent of its movement is controlled 110 by means of a headed pin 22, which is fixed to the body of the box. The projection 16 has one of its edges slightly beveled, the beveled edge being marked 16'. In this form of the invention as the cover of the box is raised 115 the projection 16 strikes the slotted plate 21 and throws it forward. The plate in its turn turns the head-gage on its pivot, and thus causes the plate to be thrown forward in the box. The further movement of the cover on 120 its pivot causes the projection 16 to pass the edge of the slotted plate 21. After the cast plate is removed the head-gage is thrown back 125 into position, and as the cover of the box is closed the spring-controlled projection is allowed to slip over the edge of the plate 21, this movement being facilitated by reason of its beveled edge 16'.

In the forms of the invention so far described the opening movement of the cover is caused 130 to automatically operate the head-gage to move it forward and displace the cast. While the invention will preferably be embodied in constructions by which a move-

ment of the cover automatically displaces the cast, it is not necessarily limited to such constructions.

In the form of the invention shown in Fig. 8 the head-gage 7 is operated by means of a sliding plate 23, the plate being connected by a pin 24 and slot 25 to a bell-crank 26 27, which is mounted between ears 28, carried by the body of the box. The bell-crank 26 27 is operated to throw the plate 23 forward and rock the head-gage by means of a spring-controlled plunger-rod 29, said rod being mounted in a bracket 30, which is secured to the frame 31 of the box, the construction being such that a downward movement of the plunger rocks the bell-crank and throws the plate 23 inward. The downward movement of the plunger may be effected in various ways. Preferably, however, the plunger is secured to a treadle 32, said treadle being pivoted on a pin 33, mounted in the frame 31. In this form of the construction it is necessary that the connection between the arm 27 of the bell-crank and its operating-rod 29 be such as to permit the casting-box to be swung upward on its trunnions in order that the molten metal may be poured into it. This connection may be of various forms. In the construction shown the rod 29 is provided with an inwardly-projecting stud 34, said stud having an open groove 35 therein, which takes over a pin 36, carried on the arm 27 of the bell-crank. As the box swings upward on its pivot, therefore, the pin 36 passes out of engagement with the groove 35. When, however, the box is swung downward into a horizontal position, as shown in Fig. 8, the pin 36 is again engaged by the groove in the stud 35, and the parts are in position so that the bell-crank 26 27 may be operated through the rod 29 and treadle 32. In this form of the invention while the head-gage is not automatically operated by the movement of the cover it is very quickly and readily operated. The operator after swinging up the cover of the box simply steps on the treadle. He does not, therefore, have to bend forward, as in the old form of box, and, furthermore, the construction affords an easy and powerful means for throwing out the plate.

The construction by which the invention is carried into effect may be widely varied. It is to be understood, therefore, that the invention is not limited to the precise constructions which have been shown and described.

What I claim is—

1. In a mold for casting stereotype-plates, the combination with the body and cover, one of said parts being movable, of means operated by the movable part for displacing the plate lengthwise of the mold, said means being thrown into operation by the act of opening the box, substantially as described.

2. In a mold for casting stereotype-plates, the combination with the body and the movable cover, of means for displacing the plate lengthwise of the mold, and devices positioned

to be operated by the cover for throwing said means into operation when the box is opened, substantially as described.

3. In a mold for casting stereotype-plates, the combination with the body and cover, of a movable head-gage, and mechanism operating on the gage for giving it a movement to displace the plate lengthwise of the mold, substantially as described.

4. In a mold for casting stereotype-plates, the combination with the body and cover, of a pivoted head-gage, and mechanism operating on the gage to swing it on its pivot whereby it displaces the plate lengthwise of the mold, substantially as described.

5. In a mold for casting stereotype-plates, the combination with the body and cover, one of said parts being movable, of a movable head-gage and means whereby the movable part moves the gage when the box is opened, the movement of the gage serving to displace the plate lengthwise of the mold, substantially as described.

6. In a casting-box, the combination with the body and cover, of a movable head-gage, and means actuated by the cover for moving said head-gage to displace the cast when the box is opened, substantially as described.

7. In a mold for casting stereotype-plates, the combination with the body and cover, of a movable head-gage, and a projection moving with the cover and operating when the cover is lifted to move the head-gage and displace the cast, substantially as described.

8. In a mold for casting stereotype-plates, the combination with the body, of a cover pivoted thereto, a head-gage, and means carried by the cover and operating to move the head-gage to displace the cast when the cover is turned on its pivot to open the box, substantially as described.

9. In a mold for casting stereotype-plates, the combination with the body, of a cover pivoted thereto, a head-gage pivoted in the box, and a projection moving with the cover and operating when the cover is turned on its pivot to swing the head-gage on its pivot and displace the cast, substantially as described.

10. In a mold for casting stereotype-plates, the combination with the body, of a cover pivoted thereto, a head-gage, and a projection moving with the cover and operating to move the head-gage to displace the cast when the cover is swung on its pivot, said projection being arranged to yield on the closing movement of the cover, substantially as described.

11. In a mold for casting stereotype-plates, the combination with the body, of a cover pivoted thereto, a head-gage, and a spring-controlled projection moving with the cover and operating to move the head-gage to displace the cast when the cover is swung on its pivot, substantially as described.

12. In a mold for casting stereotype-plates, the combination with the body, of a cover pivoted thereto, a head-gage also pivoted thereto, and a spring-controlled projection moving

with the cover and operating when the cover is swung on its pivot to swing the head-gage on its pivot and displace the cast, substantially as described.

5 13. In a mold for casting stereotype-plates, the combination with the body, of a cover pivoted thereto, a head-gage also pivoted thereto, and devices independent of the gage, said devices acting to swing the gage on its pivot to displace the cast lengthwise of the box when the box is opened, substantially as described.

14. In a mold for casting stereotype-plates, the combination with the body, of a cover pivoted thereto, a projection on the cover, and a head-gage having a part lying in the path of the projection, whereby as the cover is swung on its pivot to open the box the projection strikes the head-gage and moves it to displace the cast, substantially as described.

15 15. In a mold for casting stereotype-plates, the combination with the body, of a cover pivoted thereto, a projection on the cover, and a pivoted head-gage having a part lying in the path of the projection, whereby as the cover is swung on its pivot to open the box the projection strikes the head-gage and turns it on its pivot to displace the cast, substantially as described.

20 16. In a mold for casting stereotype-plates,

the combination with the body, of a cover pivoted thereto, a projection pivoted to the cover, and a head-gage pivoted to the body and having a part lying in the path of the projection on the cover, the projection being arranged 35 so that it strikes and moves the head-gage as the cover moves in one direction and turns on its pivot to allow the gage to pass as the cover moves in the other direction, substantially as described.

40

17. In a mold for casting stereotype-plates, the combination with the body, of a cover pivoted thereto, a projection pivoted to the cover, a spring for controlling the movement of the projection, and a head-gage pivoted to the 45 body and having a part lying in the path of the projection on the cover, the projection being arranged so that it strikes and moves the head-gage as the cover moves in one direction and turns on its pivot to allow the gage to pass as the cover moves in the other direction, substantially as described.

In testimony whereof I have hereunto set my hand in the presence of two subscribing witnesses.

EDWIN D. TUCKER.
